UNITED STATES PATENT OFFICE

2,038,636

WOOD HEEL CONCAVING MACHINE

Walter W. Bradbury, St. Louis, Mo., assignor to
 United Shoe Machinery Corporation, Paterson,
 N. J., a corporation of New Jersey

Application March 27, 1934, Serial No. 717,631

12 Claims. (Cl. 12—46)

This invention relates to machines for concav-
 ing wood heel blanks and is illustrated as em-
 bodied in that type of machine wherein a heel
 blank is held in a jack with its attaching face
 5 down on smooth table and is then automatically
 slid and turned over a cutter projecting through
 a slot in the table, with its periphery in contact
 with a gage to form the concaved attaching face
 of the heel blank. The illustrated machine gen-
 10 erally resembles a machine of this type shown in
 United States Letters Patent No. 1,902,855,
 granted March 28, 1933, on an application of M.
 W. Howard.

These machines fed the heel blank mechani-
 15 cally to the jack by means of a swinging feeder
 arm in which the heel was placed by the opera-
 tor. This arm swung the heel blank into the jack
 at a substantial velocity. The jack comprised
 20 two levers each having two rigid but adjustable
 gripping fingers on one end and a cam roller at
 the other end. As the heel moved between the
 pairs of gripping fingers it struck one end of a
 25 sliding bar having a wedge-shaped cam surface
 at its other end, located between the cam rollers.
 The sliding bar was controlled by a pair of tog-
 gle springs which normally held it in the jack
 30 open position. The blow delivered by the heel
 blank forced the bar backward, past the dead cen-
 ter of the toggle springs, which then forced it
 still farther back between the cam rollers, thus
 35 forcing the four fingers toward the heel blank.

Difficulty has been experienced with machines
 40 of this type in that a succession of commercially
 identical heel blanks were not properly held
 tightly in the jack. There are slight variations
 in such blanks as they come to the machine, and
 in many cases the blow of the heel blank and the
 45 toggle springs were unable to throw the slide bar
 back far enough to cam the rollers sufficiently to
 grasp a slightly oversize heel blank effectively,
 and then the jar which occurred as the heel blank
 contacted with the gage was liable to dislocate
 50 the heel blank a little in the gripping fingers.
 Such a heel blank was liable to be torn out of the
 machine and spoiled, and, if dislocated a little, to
 be improperly cut because of its erroneous posi-
 55 tion in the jack.

The present invention remedies this difficulty
 by providing an automatic means for throwing
 60 the sliding bar to its effective position, so that its
 range of movement is unaffected by the pressure
 of the heel blank against the gripping fingers as
 they begin to take hold. In accordance with an-
 other feature of the invention, also, any varia-
 65 tions in dimensions of the blanks are taken care

of by providing a resilient clamping finger, in
 combination with rigid clamping fingers, which
 also acts to take up or compensate for any loose-
 ness or any dislocation of the heel blank between
 the clamping levers due to initial jar against the
 5 gage and cutter, and thus avoids the throwing of
 the blank out of the machine and possible harm
 to the operator.

As already stated, the prior machine under dis-
 cussion was also provided with an automatic load-
 10 ing mechanism, wherein an arm in which the
 operator had placed a heel blank was swung to-
 ward the jack to locate the blank between the
 holding instrumentalities of the jack just before
 the jack closed. This arm then had to be quickly
 15 removed from the path of the moving jack to
 avoid damage from the moving jack. It was so
 removed by a coil spring which was distorted
 more and more by the loading movement of the
 arm. Difficulty was experienced with this device
 20 in that if the spring were made amply strong to
 insure quick enough removal of the loading arm
 from harm's way, it was liable to come to rest
 with two much of a shock, and secondly, the
 25 spring sometimes broke leaving the loading arm
 uncontrolled in the path of the moving jack, with
 consequent breakage.

The present invention remedies this difficulty
 by providing an additional resilient member act-
 30 ing only while the loading arm is in the neighbor-
 hood where it can interfere with the jack. This
 member is adequate to move the arm out of
 harm's way unassisted by the first spring dis-
 cussed, which therefore need not be as strong as it
 35 would have to be in the absence of the resilient
 member characteristic of the present invention,
 and in case this spring breaks no other harm is
 done.

These and other features of the invention com-
 40 prising certain combinations and arrangements
 of parts will be apparent from the following de-
 scription of a preferred embodiment of the inven-
 tion shown in the drawings, in which

Fig. 1 is a side elevation, partly in section, on
 the line I—I of Fig. 2;

Fig. 2 is a front elevation;

Fig. 3 is a perspective view;

Fig. 4 is a plan view of the jack and loading
 mechanism;

Fig. 5 is an underneath perspective view of the
 50 jack;

Fig. 6 is a perspective view of the jack from
 above;

Figs. 7 and 8 are plan views of the open and
 55 closed jack, respectively;

Fig. 9 is a detail of the control gear;
 Fig. 10 is a detail of a clamping finger;
 Fig. 11 is a diagram;

Figs. 12 and 13 illustrate partly finished and 5 finished cuts on the heel blank, respectively.

The main frame 10 is provided at one end with an upright pivotal axis 12 on which is suspended a generally horizontal arm 14 which carries the heel blank holding and feeding apparatus and 10 swings the heel blank above a flat table 15. This arm is always urged to swing toward a stop screw 16, mounted on the frame 10, by a strong spring 18 having one end fastened to the frame 10 and the other fastened to the arm 14. The arm will 15 not contact with this stop while a heel blank is in contact with the cutter, and the stop is provided to avoid overthrow of the arm by the spring 18 before the heel blank has been brought into contact with the gage and cutter and after it has 20 separated from them.

The arm 14 carries a horizontal gear box 20 in which is freely slidably and rotatably mounted an ovoid-shaped gear 22, the shape of which corresponds roughly to that of the attaching face of 25 a heel. This gear has a smooth flange 24 which runs against two rollers 26, 28 mounted on vertical shafts 30, 32 in the gear box. One of these shafts, as 30, carries a pinion 34, coaxing with the gear 22, and is driven from a pulley 36 at its 30 upper end.

The gear 22 has an internal smooth face 38 against which presses a roll 40 mounted on the lower end of a shaft 42 which projects through an enlarged hole in the top of the gear box 14. The 35 shaft 42 is mounted in one end of a lever 44 pivoted at 46 on the gear box cover and urged clockwise, when seen from above, by a strong spring 48 which connects its other end with a lug on the gear box. The roll 40 will thus force the 40 flange 24 to ride on the rolls 26, 28 at all times while the pinion 34 forces the gear 22 to rotate, and the position of the gear is thus definite at all times.

The gear 22 carries the jacking mechanism. 45 A stub 50 hangs from the bottom of the gear and has a dovetail rib 52 at its lower end, which carries a slide 54. The slide 54 has a dovetail rib 56 on its under surface, engaging a slide 58 which carries the jack. The slides 54, 58 are held in 50 adjusted positions by screws 57, 59 respectively. These slides enable the jack to be placed in any desired position relative to the gear 22, though its adjustments are translational and not rotatory.

The slide 58 has two depending pins 60, 62 on 55 which are pivoted at their middle portions two reversely shaped finger levers 64, 66. The lever 66 carries at one end two longitudinally adjustable fingers 68, for engaging one side of a heel blank, and the lever 64 has a similar finger 68 60 and also a finger 70. The three fingers 68 are all alike, being rigidly mounted in the finger levers. The finger 70, shown in detail in Fig. 10, is resilient. It comprises a threaded case 72 having within it a plunger 74 having a collar 76 normally abutting the flanged inner end of the case 72, and pressed toward this end by a very stiff spring 78 having its other end abutting a plug 80 in the outer end of the case. The plunger 74 yields slightly when in clamping engagement with 65 a heel, as will be seen. The four clamping fingers 68, 70 point in downwardly converging directions, and all have little leather plugs 82, in cups on their ends. These cups are frusto-conical in shape, with their small ends outward. The 70 leather plugs thus tend to wedge firmly in the

5 cups. A spring 83 tends to hold the finger levers 64, 66 in open position.

The rear ends of the levers 64, 66 carry cam rolls 84, cooperating with a generally V-shaped cam 85 mounted on the rear end of a bar 88 arranged to slide horizontally in a guide 89 mounted on the lower end of the pins 60, 62. Each side of the bar has a portion 90 parallel to the length of the bar, a diverging oblique portion 92, and another portion 94 parallel to the length of the 10 bar. When the bar 88 is in its forward position (Fig. 7) the rolls 84 rest on the narrow portion 90 of the bar and the finger levers 64, 66 are in open position: when the bar is in its rearmost position (Fig. 8) they rest on the broadest portion 94 of 15 the bar, and the pressure they exert, due to the pressure of the heel blank on the fingers 68, 70, which are now clamping it, is resisted by the surfaces 94 which are parallel to each other and to the guide 89 and are also substantially at right 20 angles to the pressure. Thus, there is no tendency to wedge the bar 88 forwardly out of locking position. The clamping action of the finger levers is positive and definite.

The bar 88 has shoulders 95 at its ends to contact with the guide 89 when the bar 88 is in its limiting positions, and carries at its rear end a roll 96 cooperating with a notch 98 in the end of a lever 99 pivoted at 100 on a lug forming a part of the slide 58. The lever 99 has rolls 102, 104 at 30 its ends, the latter being near the notch 98. The lowest part of the guide 89 has two fingers 106 which serve as a breast abutment for the heel blank when in jacked position, and the bar 88 has an end 108 which acts as an ejecting finger 35 when the jack opens to release the heel blank.

The jack is operated by a finger 110 adjustably mounted in the end of a lever 112 pivotally mounted on a bolt 114 which depends from a lug 113 on the gear case 14. A spring 116 is connected to the other end of the lever and to a lug 118, pivotally adjustable on the bolt 114, but normally clamped thereby in immovable relation to the lug 113. The lever 112 has a stop surface 120 coaxing with a stop surface 122 on the lug 118 45 to define the normal position in which the lever 112 is held by the spring 116. An abutment 124 on the lug 118 coacts with an adjusting screw 126 on the lug 113, to adjust the normal position of the lever 112 and finger 110 due to changes in 50 the adjustment of the jack by means of the slides 54, 58. The bolt 114 is loosened to effect such adjustment.

When the loading device, to be described below, throws a heel blank against the end of the bar 55 88, the bar slides back, camming the rolls 84 apart until the fingers 68, 70 contact with the blank, but this operation may not throw the bar 88 completely to its operative position. As soon as the jack starts to move, and before the heel 60 blank strikes the gage 158, to be described below, the roll 102 strikes the finger 110 and is thrown in toward the jack, forcing the bar 88 clear back to its operative clamping position and closing the fingers 68, 70 on the heel blank. When the jack 65 has been moved, in accordance with the shape of the gear 22, something less than a whole revolution, the roll 104, which has been in outward position, strikes the finger 110 and forces the jack open, and the member 108 ejects the heel blank. 70

The loading mechanism comprises a lever 132 pivoted at 133 and pressed by a spring 134 to the position shown in Figs. 3 and 4. The arm is operated by a finger 136 pivoted at 138 and having an arm 140 resiliently linked to the end of the 75

lever 130 at 141. The finger 136 is struck by the end of a finger 142 mounted on the slide 58 as the heel jack turns and is so timed that it gets the heel blank to the jack just before the finger levers close. The arm 130 has a freely adjustable heel blank back gage 142' and a clamping finger 144 mounted on it to hold a heel and slide it over the table 15. The arm is cushioned on its spring-impelled back stroke by a dash-pot 146. The pivots 132, 138 are mounted on an adjustable slide 148. The slide 148 carries also a casing 150 in which there is a sliding rod 152 which is impelled by a coil spring 154 in the casing toward the loading arm 130. This rod is forced back against its spring by the arm 130 as it moves a heel toward the jack, its spring 154 being thereby compressed. The spring 154 has sufficient strength to throw the arm 130 back out of the way of the moving jack and reinforces the action of the spring 134 in the initial part of the back stroke, it being inadvisable to make the spring 134 too strong, since such construction may cause too much slamming as the arm 130 comes to rest. Also, in case the spring 134 breaks, as sometimes happens, the parts 130, 136, 140 then swinging freely, the rod 152 will swing the arm 130 out of the range of movement of the jack. The rod 152 and spring 154 do not come into action until just before the arm 130 has moved sufficiently toward the jack to be in danger of being struck by the jack during the later part of its cycle of movement.

The cutter 156 is mounted on a horizontal shaft and projects upward through a slot in the table 15. At one end of the slot is located an adjustable gage 158 against the edge of which the heel blank rests as it is being turned by the jack.

In operating the machine, the operator puts a heel blank 160 in the loading device, as shown in Fig. 3. When the jack has turned to receiving position the finger 142 strikes the finger 136 and operates the loading device to slide the heel blank 160 over the table to a position A (Fig. 11) on the table between the opened fingers 68, 70, which are immediately closed on it by the engagement of the roll 102 with the finger 110. The heel blank is then moved toward the cutter and its edge comes in contact with the gage 158, the stop 16 then becoming inoperative, as the arm 14 is slightly forced out from it. The heel blank is then turned and slid over the cutter with its edge against the gage 158 through an angle of about 180°, passing through the successive positions shown in Fig. 11, until the roll 104 strikes the finger 110, when the jack opens and the end 108 of the bar 86 ejects the heel blank. The loading arm swings back to the position shown in Fig. 3 as soon as the finger 136 is released, the rod 152 attending to this if the spring 134 is out of commission.

During its transmittal over the cutter the heel blank 160 is first gripped between the three fingers 68, the resilient finger 70 and the fingers 106, the resilient finger 70 being set so that it must yield slightly as the jack closes. If the heel blank should strike the gage 158 with a substantial shock, and become slightly dislocated in the fingers, the finger 70 follows it and it is still held tightly in the jack. It will be noted that this finger 70 is on the same side of the heel blank at this time as is the gage 158. The finger 70 is also useful in taking up or compensating for variations in the contour of successive heel blanks as they come to the machine.

The positive locking of the jack by mechanical-

ly insuring the contact of the rolls 84 with the cam portions 94 of the bar 88 is of considerable importance. The locked positions of the finger levers 64, 66 are thus quite definite, and cannot be disarranged by a jar.

The nature of the cut is shown in Figs. 12 and 13. The cutter enters at X and follows the course indicated by the dotted line Fig. 12 until it reaches the point Y, when the heel blank turns about 180°, and then comes out at the other side of the heel 10 breast.

Having thus described my invention, what I claim as new and desire to secure by Letters Patent of the United States is:

1. A jack having two swinging finger levers, 15 and a sliding bar having opposed parallel cam surfaces coacting with the ends of the finger levers respectively to cause the other ends of the levers to close upon a work piece, whereby the pressure between the first-named lever ends and 20 the sliding bar will not tend to move the sliding bar when the jack is in holding position, and automatic means for positively throwing the sliding bar to its extreme operative position.

2. A jack comprising a guide, a sliding cam bar 25 working in the guide, a finger lever arranged to exert clamping pressure on a heel blank at one end and having its other end coacting with a cam surface on the cam bar, the pressure between the last-mentioned lever end and the cam surface 30 being substantially normal to the guide, and means operated by the initial movement of the jack from loading position for positively throwing the sliding bar to its extreme operative position.

3. A wood heel jack having a plurality of clamping abutments arranged to contact with the lateral surface of a wood heel blank, said abutments being rigid when in clamping position, and a resilient abutment arranged to follow the heel 40 blank in any dislocation due to jar.

4. In a wood heel concaving machine, a table, a cutter projecting through the table, a gage adjacent to the cutter, and a jack arranged to grip a heel blank and slide it over the table past the 45 cutter with its edge against the gage, said jack having a plurality of rigid clamping fingers contacting with a lateral surface of the blank, and a resilient finger arranged to contact similarly with a lateral surface of the blank.

5. In a wood heel concaving machine, a table, a cutter projecting through the table, a gage adjacent to the cutter, and a jack arranged to grip a heel blank and slide it over the table past the cutter with its edge against the gage, said jack 55 having a plurality of rigid clamping fingers contacting with a lateral surface of the blank, and a resilient finger arranged to contact similarly with a surface on the blank, said resilient finger being located on that side of the blank which is initially in contact with the gage, whereby the heel blank, if jarred by its initial contact with the gage, will be followed by the resilient finger and firmly held.

6. In a wood heel concaving machine, a table 65 having an aperture therein, a cutter projecting through the aperture, a gage adjacent to the edge of the aperture, a jack movable to slide and turn a heel blank on the table over the cutter with its attaching face on the table and the edge of its 70 attaching face in contact with the gage, said jack having a plurality of clamping fingers directed convergently and toward the table and arranged to engage the tapering surface of the heel blank to crowd it toward the table, one of 75

said fingers, located on that side of the heel blank that comes initially into contact with the gage, being resilient, and others of said fingers being rigid when in clamping position.

5 7. In a wood heel concaving machine, a cutter, a jack arranged to hold a heel blank and to feed it past the cutter, a loading member arranged to hold a heel blank and to move it to the jack when the jack is in loading position, resilient 10 means for opposing the loading movement of the loading member and for returning it to normal position when its heel has been delivered to the jack, and a second resilient means arranged to operate on the loading member while it is in 15 position to be struck by movement of the jack, to insure prompt removal of the loading member from said position when it is released.

8. In a wood heel concaving machine, a cutter, a jack arranged to hold a heel blank and to feed it past the cutter, a loading member arranged to hold a heel blank and to move it to the jack when the jack is in loading position, resilient 20 means for opposing the loading movement of the loading member and for returning it to normal 25 position when its heel has been delivered to the jack, and a second resilient means comprising a sliding spring-impelled rod arranged to operate on the loading member while it is in position to be struck by movement of the jack, to insure 30 prompt removal of the loading member from said position when it is released.

9. In a wood heel concaving machine, a cutter, a jack arranged to hold a heel blank and feed it past the cutter, a loading member arranged to hold a heel blank and to move it to the jack and having a delivering position and a loading position at which it is itself loaded by the operator, resilient means for holding the loading means in 35 its loading position to permit its movement toward the jack, and a second resilient means arranged to contact with the loading member after it has left its loading position and before it has reached its delivering position, whereby the action of the first resilient means is reinforced during the time that the loading member is within 40 the neighborhood of the jack.

10. In a wood heel concaving machine, a cutter, a jack arranged to hold a heel blank and feed it past the cutter, a loading member arranged to hold a heel blank and to move it to the jack and having a delivering position and a loading position 5 at which it is itself loaded by the operator, resilient means for holding the loading means in its loading position to permit its movement toward the jack, and a second resilient means comprising a spring-impelled rod located in the path 10 of the loading member and arranged to contact with the loading member after it has left its loading position and before it has reached its delivering position, whereby the action of the first resilient means is reinforced during the time that 15 the loading member is within the neighborhood of the jack.

11. In a wood heel concaving machine, a cutter, a jack arranged to hold a heel blank and feed it past the cutter, a loading member arranged to hold a heel blank and to move it to the jack and having a delivering position and a loading position at which it is itself loaded by the operator, resilient means for holding the loading means in 20 loading position to permit its movement toward 25 the jack, and a second resilient means arranged to contact with the loading member after it has left its loading position and before it has reached its delivering position, whereby the second resilient means will move the loading member from 30 the neighborhood of the jack irrespective of the action of the first resilient means.

12. A jack comprising a guide, a sliding cam bar working in the guide, a finger lever arranged to exert clamping pressure on a heel blank at 35 one end and having its other end coacting with a cam surface on the cam bar, the pressure between the last-mentioned lever end and the cam surface being substantially normal to the guide, and means operated by the initial movement of the 40 jack from loading position for positively throwing the sliding bar to its extreme operative position, the finger lever having a resilient heel blank contacting abutment to compensate for minor variations in dimensions of the heel blank. 45

WALTER W. BRADBURY.
